UNITED STATES PATENT OFFICE.

FRED W. BARKLEY, OF WINTHROP, MASSACHUSETTS, ASSIGNOR TO ALBERTO BARKLEY, OF PAINTED POST, NEW YORK.

CARRYING-OVER MECHANISM FOR CALCULATING MACHINES.

Application filed March 18, 1921. Serial No. 453,356.

The invention relates to calculating machines of the type having a suitable selecting mechanism, an operating mechanism and an overrotating device for obtaining a certain calculation which can be indicated on one or more rotary registering dials to obtain a definite or predetermined result. The invention consists of a carrying-over mechanism which brings into action each succeeding registering dial and acts positively in relation to the predetermined condition of each succeeding operation of the said registering dial. The invention further consists of a suitable mechanism to act positively in either direction of rotation of the operating members.

The object of the invention is to provide a calculating machine having an effective rotating unit for allowing certain numerals to be selected for obtaining a certain definite calculation adapted to be used with a novel carrying-over mechanism to allow the calculation to be carried over from one registering dial to the next in the order ten in either direction which is durable, practical, noiseless and cheap to manufacture.

A complete description of a calculating machine and my improvements are as follows: reference being made to the accompanying drawings of which—

Figure 1 is a longitudinal section of the casing showing the operating mechanism.

Figure 2 is a partial longitudinal section of the machine showing the keys, setting up and selecting mechanisms.

Figure 3 is a partial plan view of the machine with the cover taken off showing the internal mechanism.

Figure 4 is a side view of the carrying-over mechanism.

Figure 5 is a front elevation in partial diagrammatic form showing the carrying-over mechanism.

Figure 6 is a side view of the same.

Figure 7 is a plan view of the carrying-over mechanism.

Figure 8 shows the carrying-over mechanism in the operating position.

Figure 9 is a diagrammatic view showing the selecting strip.

The machine is provided with operating keys ranging from 0, 1, 2, 3, 4, 5, 6, 7, 8 and 9 inclusive, which are connected to, and set up the calculating mechanism. The calculating mechanism is located in a suitable

casing 10, having a cover 11, and a transverse sliding carriage 12. Formed on the sliding carriage 12 is an operating finger 13, for lifting the carriage and moving it back and forth across the machine and calculating mechanism in accordance with the calculating operations required. Also formed on the carriage 12 is a catch 14 which cooperates with the holes 15 formed in the cover 11, which registers with the set of dial and mechanism required to perform a certain calculation. Mounted in the casing 11 are several sets of operating keys. Six sets are commonly used but as many sets can be used as is necessary in accordance with the size of the machine. Each set of keys operates the numeral from zero to nine inclusive, and each succeeding set will be indicated by numerals and small letters *a*, *b*, *c*, etc. As each set of keys and operating parts are identical in construction, a description of one will be sufficient. The six sets of keys will give a range of calculation from 1 to 999,999 and further calculations may be obtained by manipulating the carriage 12.

When the numerals are selected to be calculated the results are obtained by rotating the crank 16. To obtain a result in addition and multiplication the crank is turned in one direction, and for subtraction and division the crank is turned in the opposite direction. The result of the calculation is shown through the window 17, formed in the carriage 12. To clear out the figured calculation, the dials are returned to the zero position by the handle 18, which controls the clearout mechanism, the numeral showing through the windows 17 indicate the numeral result determined by the keys from 1 to 9 inclusive and the operation of the crank 16 in relation to a given formula to be calculated. Each of the six sets of selecting keys are marked with ten numerals ranging from zero to nine, which controls the rotating registering dial and each succeeding dial marking in the next order of ten in either direction. The mechanism for carrying-over the calculation in the order of ten from one dial to the next succeeding one, is novel and is the main embodiment of my invention. The keys, zero to nine, *a*, *b*, *c*, etc., are mounted in a housing secured to the cover 11 which allows the keys to be readily placed in position or taken out as the condition requires. The keys are

guided in their vertical movement by the free to move axially thereon within the range of the cage gear 30. This range of movement allows the selecting mechanism to operate within the range of numeral from 1 to 9 inclusive. The selecting mechanism is controlled by the operating handle 16, shaft 31, which is a part of the handle 16, bevel gears 32 and 33. Shaft 34 which is provided with suitable bearings, bevel gears 35 and 36, and shaft 37. The shaft 37 extends across the machine and is adapted to receive a plurality of disks 38, on which a part of the selecting mechanism is mounted. The part of the selecting mechanism mounted on the disks, 38, consists of nine strips 39, made preferably of metal and each strip is indicated by 1, 2, 3, 4, 5, 6, 7, 8 and 9 corresponding to the keys operated to obtain a certain operation. The nine strips 39, etc., are each provided with a depression 40, each strip having a tooth of different length. Each one of these strips will mesh with a corresponding tooth on the gear 28, and if the said gear 28 is moved axially along the shaft by the key 5, strips 1 to 5 inclusive of strips 39 if rotated will mesh with a corresponding number of teeth on the gear 28, thereby moving the distance of five teeth. If any one of the keys from 1 to 9 inclusive is operated it will move the gear 28 axially on the shaft 29 into a position to be operated by the corresponding strip indicated. When a numeral is selected the key bearing that numeral will be pressed downwardly, thereby, moving the gear 28 axially on the shaft 29 to a position corresponding to the key selected. The operating handle is then rotated in the direction desired which causes the disks 38 and strips 39 to rotate one revolution. By this operation the strips 39 corresponding to the key depressed causes the gear 28 to rotate the distance or numeral designated. The rotating movement of the gear 28 is communicated to the registering dial 41, 41^a, 41^b, 41^c, etc., through the cage gear 30, intermediate gear 42 and dial gear 43 thereby showing the result of the calculation on that particular dial 41, 41^a, 41^b, 41^c, etc. A suitable overthrew check device is provided to prevent the dial from over rotating the position designated by the keys, and consists of a pawl lever 44 loosely mounted on the shaft 45 and is free to be controlled by the cam surfaces on the disk 38, which allows the pawls 46 to disengage the gear 42 and allows the operation to take place. In the reverse operation the shaft 45 and arm 47 turns in the direction to engage the pin 48 and lift the pawl lever 44 away from the cam surface on the disk 38 and transfer the stress of the over rotating operation to the pawl 46 and spring 49.

When the calculation requires a greater numeral than nine on any one dial a carry-over mechanism is provided to automatically

When the numeral 9 is used the sliding plate 22 is moved the longest distance which would cause the setting-up mechanism to be moved a corresponding amount to bring the numeral 9 to view on the registering dial. All intervening numerals, when used, would cause the setting-up mechanism to be moved correspondingly to bring the numeral to view in the registering dial.

Mounted on the stationary plate 21 are the bell cranks 25 a, b, c, etc., corresponding to the number of banks of keys used which is operated by the sliding plate 22 a, b, c, etc. The bell crank 25 is fulcrumed at 26 on the stationary plate 21. Integral with the bell crank 25 is a projection 27, which cooperates with the sliding plate 22 for swinging the bell crank 25 into the designated position determined by the operation of any one of the keys from 1 to 9 inclusive. The swinging movement of the bell crank 25 imparts an axial movement to the gear 28, mounted on the shaft 29. The gear 28 rotates on the shaft 29 and also is

- cally carry over the result to the next dial in the order of ten. For example, in a calculation of addition, five and five is added together which necessitates the use of the 5 key 5 and the turning of the operating crank 16 twice, thereby turning the dial 41^a one revolution and registering zero, and also turn the next dial which will register one, thereby making a total reading of ten. 10 The embodiment of my invention lies in providing a device of this character which is accurate in operation and cheap to manufacture. The invention can best be understood by referring to Figures 4, 5, 6 and 7. 15 Secured to the gear 43 is a pin 50, Figure 5, which is brought into action in addition and multiplication when the gear 43 is rotated to the last tooth or nine-tenths of its revolution. In this position further movement of 20 the gear 43 on which the pin 50 is located, engages the bevel end 51 of the arm 52, thereby carrying with it the lever 53 having the projection 54 integral therewith, into the path of the cam 55 of the carrying-over 25 finger 56 which causes it to engage the intermediate gear 42, which in turn operates the dial gear 43 and dial 41 of the next higher order registering the amount. 30 In subtraction and division the dial gear 43 travels in the opposite direction, and the pin 50 instantly engages the opposite side of the bevel surface 51 on the arm 52, forcing it downwardly for the carrying-over operation. The lever 52 is integral with 35 the lever 53, the two levers being connected by the cross-piece 57. The downward movement of the lever 52 is communicated to the lever 53 and causes it to be released from the spring catch 58, at the same time allowing 40 the projection 54, formed on the lever 53 to drop into the path of the carrying-over finger 56. The spring catch 58 is secured to the stationary collar 60 by a screw. The carrying-over finger 56 is pivotally secured to the disks 38 as shown in Figures 45 4, 5 and 6. The portion of the carrying-over mechanism extends through the disk 38 and is pivoted through the lug 61, Figure 6, sufficient clearance being provided to 50 allow the member to swing upwardly. Extending across to the next disk is an arm 62, which is held from sidewise movements by the slot 63, Figure 5, but is free to move upwardly to the height of the said slot 63, 55 as shown in Figure 5. The upper part of the device is formed into two bevel cam surfaces 55 in the form of the letter A. Integral with this is the tooth portion 66 which engages the gear 43 of the next set, 60 that is, when the lever 48 drops down to the position shown in Figure 8, the bevel cam surfaces 55 wipes against it and causes the tooth portion 66 to move in the path of rotation to engage the tooth of the gear 43 65 of the next dial gear 42^a. Formed in the
- disk 38 is an offset projection 67 which, in its path of rotation, comes into contact with the projection 54 formed on the lever 53, which forces it back into the spring catch 58 as shown in Figure 4. 70
- All operating parts of the machine work the same in both directions, with the exception of the over-rotating check and the carrying-over mechanism, the latter being the embodiment of my invention. In the reverse position a duplicate carrying-over mechanism 56 is employed. The construction and operation of the carrying-over mechanism is identical, as it is set in a position in the disk to allow the carrying-over 75 operation to take place at the proper time. 80
- In the reverse operation, which is used in subtraction and division calculations, the carrying-over mechanism is located in five of the disks. In order to prevent all five 85 of them from operating together, they are set in a spiral relation on the disk and in relation to themselves, so that if one carrying-over mechanism operates at a certain time, the next one will be several degrees before or after, according to the direction of rotation. 90
- In operation, calculations are performed in addition, subtraction, multiplication and division. These calculations call for distinct and complete operation of the mechanism, for determining the result of the calculation. A standard adding machine keyboard is used for setting up numbers to be added, subtracted and divided and forms 95 part of the selecting mechanism. In proper relation to the keyboard is a suitable crank 16 for performing the operation of calculation. On the back of the machine is a carriage holding the dial 41, 41^a, 41^b, 41^c, etc. which 100 shows the results and proofs of the operations as they are performed. The crank 16 can operate clockwise and counter-clockwise. In examples of multiplication and addition the crank is turned in one direction, and for subtraction and division the crank is turned in the opposite direction. 105 When the zero keys are pressed downwardly it is only for releasing the other keys in the same bank which have been used. The carriage 12, having the result dials mounted therein, may be shifted to the right or to the left with ease and accuracy to obtain the results in conjunction with the selecting and operating mechanism. To obtain a result in 110 addition or multiplication any of the keys from 1 to 9 inclusive, in as many sets of banks of keys as desired may be pressed downwardly and held by a suitable lock until the other key is operated in the same bank of keys 115 when it is unlocked or when it is clearly out after the calculating operation has taken place. This downward movement of the keys in their respective bank causes the sliding plate 22 to move to the right, thereby 120 125 130

imparting a swinging movement to the bell crank lever 25. As the bell crank lever 25 swings on its pivot it causes the selecting gear 28 to move axially within the range 5 limited by the cage gear 30. The operating crank 16 is then turned one revolution which causes the disk 38 to turn in the direction of the arrow A, Figure 2, thereby, bringing one of the respective gear bars from 1 to 9 10 inclusive, into mesh with—gear 28, and causing it to turn, registering the numeral or key previously set up. This movement of rotation of the gear 28 imparts a proportional movement of rotation to the cage 15 gear 42, intermediate gear 43, dial gear 44, and dial 41, thereby showing the result or numeral through window 17. When any of the strip bars from 1 to 9 inclusive are in line to engage the gear 28, the over-rotating lever 44 drops down into one of the 20 lower cam surfaces formed on the disk 38, to cause the pawl 44 to move out of the path of rotation of the gear 42, thereby allowing the whole train of gears and dial 41 25 to rotate as designated. Further rotation of the disk 38 will cause the over-rotating check lever to be raised to the upper cam surface, and the gears are again locked in position until the next operation.

30 In subtraction and division the operating crank 16 is turned in the opposite direction. One revolution causes the disks 38 and selecting bars from 1 to 9 inclusive to rotate in the opposite direction as well as 35 all the other rotating members thereby showing the predetermined results through the window 17 of the carriage 12. During the reverse operation, the over-rotating check is again brought into action by a special 40 device which causes the shaft 45 to be rotated sufficiently to cause the pin 47 to turn and engage the pin 48 on the pawl lever 44, and lift it out of the path of the cam surfaces formed on the disk 38, thereby holding it 45 rigidly in position and transferring the over-rotation friction of the pawl to the spring 49 the tension of which is sufficient to prevent it from over-rotating but allows it to rotate when power is used.

50 When the calculating operation is carried over from one registering dial to the next in the order of ten, a special device is provided constituting the main embodiment of 55 my invention. When the carrying-over mechanism reaches a certain position, the tooth 9 of dial gear 43 has reached a point where the result is to be carried over to the next dial by my special device. The carrying-over operation depends first on the pin 50, 60 located on tooth 9 of the gear 43. The rotating movement of the pin 50 causes it to wipe against the bevel surface of the yoke levers 52 and 53 causing the latch 54 on the said lever 53 to be released from the catch 65 58 permitting it to drop to the position

shown in Figure 8 for moving the gear the predetermined distance to show the designated calculation. In the reverse movement the pin 46 engages the opposite side of the bevel surface formed in the arm 52, forcing it 70 down in the same manner as before to complete the carrying-over operation. By this movement the projection is brought into the path of the gear causing the pivot to swing outwardly into the path of the gear, thus 75 imparting a rotating movement thereto and carrying-over the result of the operation to the next dial.

In the reverse carrying-over movement the mechanism is the same except a duplicate 80 carrying-over lever is used at a different time to perform the reverse operation.

In accordance with the provisions of the patent statute I have described the principles of operation of my invention together 85 with the apparatus I now consider to represent the best embodiment thereof, but I desire to have it understood that the apparatus shown is only an illustration and that the invention may be carried out by other means. 90

The subject matter disclosed, but not claimed in the present application forms the subject matter of a co-pending application, filed March 18, 1921, Serial Number 453, 95

What I claim as new and desire to secure by Letters Patent of the United States is

1. In a calculating mechanism, the combination of a setting-up mechanism, a selecting mechanism, and a registering mechanism, 100 a working shaft parallel to the shaft carrying the registering dial and intermediate gears, an over-rotating mechanism mounted on the shaft, a transfer arm also mounted on the shaft, a means on the registering mechanism for operating the transfer arm in one direction, a locking means for the transfer arm on the intermediate gear shaft, a means on the transfer arm and the selecting mechanism for operating the next gear 105 in the order of ten, and means on the transfer arm and selecting mechanism for operating the transfer arm in the opposite direction. 110

2. In a calculating machine the combination of a setting up mechanism, a selecting mechanism having a plurality of disks, an operating mechanism, and a registering mechanism, two stationary shafts parallel to the shafts carrying the registering mechanism, pins on the dial elements of the registering mechanism, transfer arms integral with each other on one of the shafts one of which arms co-operates with the pins for operating the said arm, a downwardly extending lug on the second of the arms, a detent spring on the other shaft co-operating with the second arm for retaining both arms in an operative or a non-operative position, a finger pivotally secured to the selecting 115

mechanism disks constantly spring pressed in one direction, a gear tooth integral with the finger, a double faced cam also integral with the finger acting against the spring and co-operating with the lug integral with the lever transfer arm for co-operating with the next dial in the order of ten, a V-shaped projection integral with the selecting mechanism disks which engages the lug on the transfer arm for restoring the said transfer arm to the non-operating position after the operation is completed.

3. In a calculating machine the combination of a setting up mechanism, a selecting mechanism having a plurality of disks, and an operating mechanism, and a registering mechanism, two shafts parallel to the shafts carrying the registering mechanism, pins on the dial elements of the registering mechanism, a transfer means on one of the stationary shafts, a detent means on the other stationary shaft for retaining the transfer means in either an operative or a non-operative position, a finger on the selecting disks constantly spring pressed in one direction, a gear tooth integral with the finger, a double faced cam also integral with the finger acting against the spring which co-operates with the transfer arm for operating the next dial in the order of ten.

4. In a calculating machine the combination of a setting up mechanism, a selecting mechanism having a plurality of disks, and an operating mechanism, two stationary shafts parallel to each other and to the shaft of the registering mechanism, pins on the dial element, transfer arms integral with each other on one of the shafts one of which co-operates with the pins for operating the said arm, a downwardly extending lug on one of the arms, a detent spring on the other shaft co-operating with the other arm for retaining both arms in an operative or a non-operative position, a finger pivotally secured to the selecting mechanism disks constantly spring pressed in one direction, a gear tooth integral with the finger, a double faced cam also integral with the finger acting against the spring and co-operating with the lug integral with the lever transfer arm for co-operating with the next dial in the order of ten, a V-shaped projection integral with the selecting mechanism disks which engages the lug or the transfer arm for restoring the said transfer arm to the non-

operating position after the operation is completed.

5. In a calculating machine, a selecting mechanism including disks, registering mechanism including dials, and a carrying over mechanism including an element to be operated by one of said dials, means on one of said disks to be engaged by said element following actuation thereof by a dial, said disk-carried means when set being in position to actuate an independent dial.

6. In a calculating machine, a selecting mechanism including disks, registering mechanism including dials, a lever operated by one of said dials in a predetermined position of the latter, a carrying over finger pivotally mounted on one of said disks and adapted to be moved to an operative position by said lever following operation of the latter, and means on said finger to operate another dial in a succeeding operation of the registering mechanism.

7. In a calculating machine, selecting mechanism, registering mechanism, a shaft, a transfer lever mounted on the shaft and operative by the registering mechanism, a carrying-over finger carried by the selecting mechanism capable of being positioned to operate the registering mechanism during movement of the selecting mechanism, and a cam on the lever to engage and operatively position said finger.

8. In a calculating machine selecting mechanism including disks, registering mechanism including dials, a transfer lever operative in a predetermined position of one of the dials, a carrying-over finger carried by one of the disks and adapted to be engaged and positioned by said lever, said finger when set being in position to operate one of said dials, and means on the disk for returning the lever to normal position.

9. In a calculating machine, a carrying over mechanism including means to be operatively set by one of the dials, when such dial has reached a predetermined position, and means carried by the selecting mechanism and movable therewith to be engaged by said first mentioned means and operatively set to cooperate with the next succeeding dial for advancing the registering mechanism, the means carried by the selecting mechanism being mounted for pivotal movement relative thereto.

FRED W. BARKLEY.
